UNITED STATES PATENT OFFICE.

JOHN F. BRIDGES, OF ALAMEDA, CALIFORNIA.

ROTARY ENGINE.

No. 828,997.

Specification of Letters Patent.

Patented Aug. 21, 1906.

Application filed August 15, 1905. Serial No. 274,303.

To all whom it may concern:

Be it known that I, JOHN F. BRIDGES, a citizen of the United States of America, residing at Alameda, county of Alameda, and State 5 of California, have invented certain new and useful Improvements in Rotary Engines; and I hereby declare the following to be a full, clear, and exact description of the same, reference being had to the accompanying drawings, forming a part of this specification.

This invention relates to certain improvements in motive engines impelled by a fluid under pressure and to a means of translating the reciprocal action of pistons into rotary 15 motion and force, also relates in the case of inelastic fluids to a means of measuring the volume that passes through the engine.

My improvements consist in a plurality of cylinders and pistons set and acting radially 20 from a center around which they revolve, these cylinders having trunnions through which the impelling fluid is admitted and from which the turning force is transmitted, the pistons on their outward or acting stroke 25 bearing within a guideway set elliptical to the circle of revolution, producing oblique pressure on the pistons and the required torque or turning force, which can be modified by the form of the ellipse, applied as a 30 motive engine to any useful purpose.

The object of my invention is to provide a simple fluid-engine to operate with reciprocating pistons, the wearing-surfaces moving at uniform velocity, the operating parts set 35 concentric to produce rotary motion without cranks and above certain velocities by centrifugal force confine strain on the reciprocating parts to one direction, the whole being balanced in all positions.

To these ends I construct motive engines 40 substantially as shown in the drawings here-with and forming a part of this specification.

Figure I is a front view, partially in section, of a motive engine constructed according to 45 my invention; Fig. II, a central vertical section through the same engine; Fig. III, a rear view of the engine reverse to Fig. I. Fig. IV is a transverse section through the induction-trunnion on the line *a* in Fig. II. Fig. V is a 50 partial section on the same line in Fig. II to indicate adjustment of the parts.

Referring to the drawings and the numerals of reference thereon, 1 is the main or supporting frame constituting on its interior an elliptical guideway 2, its section reinforced by

webs 3 and 4 and otherwise, if required, and provided with a base-flange 5.

7 and 8 are plates bolted to the sides of the frame 1, having purposes, as hereinafter explained.

9 and 10 are reciprocating pistons of the usual construction, provided at their outer ends with rollers 12, that bear within the elliptical guideway 2, resisting and deflecting the thrust of the pistons. These rollers 12 65 are mounted in bearings 13, made integral with the pistons 9 and 10, that have at their outer ends guide-blocks 14, that slide in the slots 15, formed in extensions of the cylinder 20, so the turning strain is imparted to the 70 latter and does not fall upon the pistons.

The rear side plate 8 forms a support for the trunnion-shaft 17, from which the power of the engine is transmitted, also contains eduction or exhaust passages 18, through 75 which the spent fluid from the cylinder 20 escapes in the usual manner either into the air or into conducting pipes. Fluid under pressure is admitted through a pipe 22, passes through the ports 24 in the trunnions 23, into 80 the chamber 28, and thence through the port or passage 27 into the cylinder 20, between the pistons 9 and 10.

Around the trunnion 23 is an adjustable shell 29, having a port or passage 33. This 85 shell is turned by a handle 30 and held by a plate 32 and is employed to regulate and vary the point of induction and cut-off accordingly as the port or passage 33 is advanced or moved back, as indicated in Figs. IV and 90 V, where the port 33 is shown of different widths to modify different points of admission.

The cylinders 20 are exhausted by the pistons 9 and 10, uncovering the ports 19 and coinciding with the ports 18 in the side plate 95 8, as will be understood, as will also the distribution functions of the trunnion 23, which are common to rotative distributing-valves of the type.

In employing steam as a motive fluid a 100 branched exhaust-pipe can be attached to the side plate 8, as indicated in Fig. III, and other modifications made to suit the temperature and nature of the fluid employed, which can be steam, gas, air, or water.

In operating the impelling fluid is admitted between the pistons 9 and 10 when in their inward position or as shown in Figs. I and II, forcing these outward and pressing the rollers 12 against the elliptical guideway 110

2, which by its obliquity, except at the centers 16, produces a turning force on the cylinders 20 and the trunnion 17 as the line of pressure varies from a tangent at the point where the 5 rollers 12 bear. This turning motion is accelerated and modified by the geometric form of the elliptical guideway 2 and can be varied to produce a motion like a crank or modifications thereof not necessary to be analyzed here. This guideway can be amplified into 10 three or more stages with the number of pistons accordingly. The guideway 2 is, as shown in Fig. I, composed of portions of two ellipses joined to form an apex at opposite 15 points 40. The object of this construction is to avoid a dead-center and give quick recovery of the turning moment after passing this point. Said points 40 can be more or less acute, as will be understood, and they constitute 20 an operative feature of much consequence in an engine of two pistons only. In this manner of operating it will be seen that in operating there are no loose pieces except the bearing-rollers 12, that all bearing-surfaces 25 have uniform speed, and that the centrifugal strain on the pistons will at ordinary

speed overbalance the fluid-pressure, and thus prevent lost motion and noise.

The engine with slight modification can be adapted to measure the volume of inelastic 30 fluids, the manner of operating remaining the same.

Having thus described the nature and objects of my invention, what I claim as new, and desire to secure by Letters Patent, is— 35

In a fluid-engine, a plurality of motive pistons and cylinders radially and revolvably mounted within an inclosing guideway of elliptical form, means to admit an impelling fluid between the pistons to force them outward against said elliptical guideway, and bearing-rollers in the outer end of each piston whose bearings slide in slots formed in extensions of the cylinders, substantially as specified. 40

In testimony whereof I have signed my name to this specification in the presence of two subscribing witnesses.

JOHN F. BRIDGES.
